UNITED STATES PATENT OFFICE.

TALBERT W. BLAKESLEE, OF ERIE, PENNSYLVANIA.

SYRINGE.

1,173,093.

Specification of Letters Patent. Patented Feb. 22, 1916.

Application filed January 16, 1915. Serial No. 2,726.

To all whom it may concern:

Be it known that I, TALBERT W. BLAKESLEE, a citizen of the United States, residing at Erie, in the county of Erie and State of Pennsylvania, have invented new and useful Improvements in Syringes, of which the following is a specification.

The invention relates to syringes, and more particularly to the class of sanitary douche syringes.

The primary objects of the invention is the provision of a syringe, wherein the spray end thereof forms a seat for the external os or end of the womb, and prevents the fluid used in the syringe from entering the said womb, thereby preventing injury thereto, yet the fluid will be free to flow so as to reach the sides of the os and cervix for the spraying of the vagina in the treatment of diseases thereof.

Another object of the invention is the provision of a syringe of this character wherein the same is of novel form to permit the introduction of the said syringe into the vagina, without pain or injury thereto, as to enable the perfect treatment of the vaginal tract and uterus, without liability of the fluid used from gaining an entrance to the womb, which would possibly result in a hemorrhage or an abortion, should the female be pregnant.

A further object of the invention is the provision of a syringe of this character which is extremely simple in construction, reliable and efficient in operation, strong, durable, and inexpensive in manufacture.

With these and other objects in view, the invention consists in the features of construction, combination and arrangement of parts as will be herein after fully described, illustrated in the accompanying drawings, and pointed out in the claims hereunto appended.

In the drawings: Figure 1, is a side elevation of a syringe constructed in accordance with the invention. Fig. 2, is a vertical longitudinal sectional view thereof. Fig. 3, is an end elevation. Fig. 4, is a sectional view on the line 4-4 of Fig. 1.

Similar reference characters indicate corresponding parts throughout the several views in the drawings.

Referring to the drawings in detail, the syringe comprises a hollow stem 5, preferably made from metal, having at one end a nipple 6, for the connection therewith of a

hose which is adapted to supply fluid to the said stem, for the treatment of diseases of the vagina. The opposite end of the stem 5, has formed thereon or fitted thereto a nozzle 7, which is of circular formation having a concaved portion 8, providing a seat or rest for the external os to prevent fluid from entering the womb, the nozzle 7, being formed with apertures 9, disposed concentrically about the concaved portion 8, while in the peripheral rounded edge 10, of the said nozzle are also apertures 11, which together with the apertures 9 discharge the fluid and spray the same onto the sides of the os and cervix, as well as washing the sides of the vagina, for the treatment of the diseased portions thereof.

The stem 5, is slidably passed centrally through a disk 12, in which are secured resilient spreader fingers 13, forming a cage for the stem 5 and nozzle 7, the said stem being fitted with a spreader disk 14, which acts upon the fingers 13 for the spreading thereof on movement of the stem 5 in one direction, each finger being formed from a single wire having its ends fastened in the disk 12, and these fingers are slightly outwardly bowed at 15 near their free ends, so that the latter will rest within a groove 16 formed in the nozzle 7, when the same is projected beyond the free ends of the fingers, thereby serving to guard the free ends of the latter, to prevent the same from injuring the end of the womb or the external os, after the syringe has been inserted in the vagina.

Surrounding the cage at its inner end is a resilient sleeve 17, the fingers 13 being outwardly bent to form flared portions 18, at their inner ends to prevent the collapsing of the sleeve, which serves as a closure plug for the mouth of the vagina. The larger end of the sleeve 17 is formed with an inturned annular flange 19 to engage over the marginal edge of a drain or discharge cup 20 provided with a discharge nipple 21, over which fits a hose for the discharge of the used fluid from the vagina, the cup 20 being formed with a tapering boss 22 through which slides the stem 5, which has secured thereto a cross finger hold or handle 23, to permit the same to be actuated, when the syringe is used. Mounted on the stem 5 and abutting against the handle 23 is a resilient collar 24, which is adapted to enter and engage in the boss 22, on moving the stem 5 inwardly of the cage, so as to prevent leak-

age about the latter of the fluid in the drain cup 20, while the syringe is in use.

In the use of the syringe the stem 5 is pulled outwardly to bring the nozzle 7 fully 5 within the flared end of the cage, so that the outer ends of the finger 13 will come together, whereupon the syringe is now ready to be inserted in position within the 10 vagina, and after this has been done the stem 5 is pushed inwardly of the cage for the spreading of the fingers 13, by the spreader disk 14, for the opening of the 15 vagina, to permit the spraying of the walls thereof with the fluid introduced through the nozzle, for the treatment of diseases of the said vagina.

From the foregoing it is thought that the construction and operation of the syringe will be clearly understood and therefore a 20 more extended explanation has been omitted.

What is claimed is:—

1. A syringe of the class described comprising a stem having a nipple at one end, a flared nozzle at the opposite end of the stem 25 and having a concaved outer concentrically perforated surface, a perforated rounded peripheral edge, and a reduced annular portion forming a shoulder rearwardly of the rounded edge, a discharge cup loosely fitted 30 on the stem to permit sliding movement of the latter therethrough and having a central forwardly tapering hollow boss, a handle fixed to the stem, a packing ring surrounding the stem and working against the handle for engagement in the hollow boss to form a sealed joint between the cup and the said stem, a cage fixed to the cup and concentrically disposed about the stem and having resilient spreader fingers, means on the stem for spreading the 35 said fingers on the sliding of the stem, a resilient sleeve surrounding the cage and detachably engaged with the periphery of 70 the cup, the said resilient fingers being formed with slightly outwardly bowed free ends to engage and become seated against the shoulder on the nozzle rearwardly of the rounded edge thereof, and a nipple integral 75 with and protruding from the cup.
2. A syringe of the class described comprising a stem having a nipple at one end, a flared nozzle at the opposite end of the stem 50 and having a concaved outer concentrically perforated surface, a perforated rounded peripheral edge, and a reduced annular portion forming a shoulder rearwardly of the rounded edge, a discharge cup loosely fitted 55 on the stem to permit sliding movement of the latter therethrough and having a central forwardly tapering hollow boss, a handle fixed to the stem, a packing ring surrounding the stem and working against the handle for engagement in the hollow boss to form a sealed joint between the cup and the said stem, a cage fixed to the cup and concentrically disposed about the stem and having resilient spreader fingers, means on the stem for spreading the 60 said fingers on the sliding of the stem, a resilient sleeve surrounding the cage and detachably engaged with the periphery of 70 the cup, the said resilient fingers being formed with slightly outwardly bowed free ends to engage and become seated against the shoulder on the nozzle rearwardly of the rounded edge thereof, and a nipple integral 75 with and protruding from the cup.

In testimony whereof I affix my signature in presence of two witnesses.

TALBERT W. BLAKESLEE.
